HOLDER FOR HIGHWAY FLARES

George L. Kernan, 1810 Market Ave.,
San Pablo, Calif. 94806

Filed Oct. 30, 1970, Ser. No. 25,736

Term of patent 14 years

Int. Cl. D29—02

U.S. Cl. D72—1

FIG_1

FIG_2

FIG_3

FIG_4

FIG_5

FIG_6

FIG. 1 is a perspective view of a holder for highway flares showing my new design;

FIG. 2 is a top plan view thereof;

FIG. 3 is a side elevational view thereof;

FIG. 4 is a perspective view of a second embodiment of my design;

FIG. 5 is a top plan view of the embodiment shown in FIG. 4; and

FIG. 6 is a side elevational view of the embodiment shown in FIG. 4.

I claim:

The ornamental design for a holder for highway flares, substantially as shown and described.
